UNITED STATES PATENT OFFICE.

DAVID P. OSBORN, OF NORWALK, CONNECTICUT.

DESIGN FOR A MARKING-GAGE.

SPECIFICATION forming part of Design No. 25,357, dated April 7, 1896.

Application filed March 9, 1896. Serial No. 582,492. Term of patent 8 years.

To all whom it may concern:

Be it known that I, DAVID P. OSBORN, a citizen of the United States, residing at Norwalk, county of Fairfield, State of Connecticut, have invented and produced a new and original Design for a Marking-Gage, of which the following is a specification, reference being had to the accompanying drawings, forming a part thereof, wherein—

Figure 1 shows a perspective view of my design, and Fig. 2 shows a cross-section on line $\alpha\alpha$ of Fig. 1.

The leading or characteristic feature of my design consists of a circular band of a truncated cone form, the upper edge whereof com-

prises a series of scallops, and the under surface of said band being slightly concaved or having the contour of the surface of a section of a sphere.

A represents the circular band, and α represents the scallops on the upper edge thereof.

What I claim, and desire to secure by Letters Patent of the United States, is—

The design for a marking-gage, substantially as herein shown and described.

DAVID P. OSBORN.
